UNITED STATES PATENT OFFICE.

FRANK HOBART, OF MARSEILLES, ILLINOIS.

FENCEPOST BASE.

Application filed July 23, 1923. Serial No. 653,219.

To all whom it may concern:

Be it known that I, FRANK HOBART, a citizen of the United States, residing at Marseilles, in the county of La Salle and State of Illinois, have invented certain new and useful Improvements in Fencepost Bases, of which the following is a specification.

This invention relates to a concrete base for fence posts, and has for its object to provide, in a manner as hereinafter set forth, a durable concrete base for wooden fence posts, adapted to be applied to the same both in the construction of fences and in repair work and which affords a firm support, as well as an anchor for the post, and which is provided with means embedded therein and projecting therefrom for engagement into the post for fixedly securing the latter to the base whereby the post will be maintained in an upright position.

Further objects of the invention are to provide in a manner as hereinafter referred to, a concrete base for the purpose set forth, which is simple in its construction and arrangement, strong, compact, thoroughly efficient in its use, readily set up, obtaining when used a great saving in fence posts cost, and inexpensive to manufacture.

With the foregoing and other objects in view, the invention consists of the novel construction, combination and arrangement of parts, as hereinafter more specifically described and illustrated in the accompanying drawings wherein is shown an embodiment of the invention, but it is to be understood that changes, variations and modifications can be resorted to which fall within the scope of the claims hereunto appended.

In the drawings wherein like reference characters denote corresponding parts throughout the several views:—

Figure 1 is an elevation, partly in section, of a base in accordance with this invention, showing supported thereby and connected therewith, a vertically disposed fence post.

Fig. 2 is a perspective view of a concrete base for fence posts in accordance with this invention, looking toward one side thereof.

Fig. 3 is a view similar to Fig. 2, looking toward the other side thereof.

Fig. 4 is a perspective view of the combined reinforcing and coupling member.

A base for fence posts in accordance with this invention, is constructed of concrete, and

comprises a vertically disposed rectangular body portion 1 of substantial thickness and which has its front face 2, as well as its rear face 3, countersunk to provide a recess 4 having the top and bottom walls, as well as the side walls thereof, bevelled, as indicated at 5. The recess 4 in the front face 2, as well as in the rear face 3, of the body portion 1, is disposed centrally thereof, or off center, in a manner as illustrated, and which is the preferred arrangement.

In the manner of setting up the recess 4, with respect to the front and rear faces of the body portion 1, the top wall of the recess is positioned a greater distance from the top of the body portion than the distance between the bottom wall of the recess and the bottom of the body portion.

Formed integral with the top 6, of the body portion 1, at a point between the center and one end of said top 6, is a vertically disposed squared extension 7, of substantial height, and with the extension preferably of a length equal to the length of the body portion 1. That part of the top 6 of the body portion 1, which is free of the extension 7, constitutes a seat upon which is mounted the base 8 of a wooden fence post 9. The inner side of the extension 7, constitutes an abutment against which is positioned the post 9.

Embedded within the extension 7, as well as the upper part of the body portion 1, and further projecting through the top of the body portion 1, that is to say, that part of the top 6 which is free of the extension 7, is a combined reinforcing and coupling member formed from a length of wire of the desired diameter and which is hook-shaped in contour and which comprises a curved shank 10, and an angle-shaped extension 11 which projects from the lower terminus of the shank 10. The shank is so set up that its lower portion will be disposed perpendicular with respect to the extension 7 and body portion 1 and with its upper portion curving outwardly toward the outer side of the extension 7. The upper terminus of the combined reinforcing and coupling member, is bent upon itself to provide an eye 12, which is positioned in proximity to the outer side of the extension 7. The vertical leg of the angle-shaped extension 11 extends a substantial distance above or through that part of the top 6, of the body

portion 1, which is free of the extension 7, and the said vertical leg of the extension 11, is adapted to engage into the bottom of the post 9, as indicated at 13, in Fig. 1, whereby the post is connected to the body portion.

The post 9 is also connected to the extension 7, and for such purpose, a hold fast device, in the form of an elongated screw 14, is employed, and which extends through the eye 12, as well as projects from the inner side of the extension 7, and engages in the post 9, as indicated at 15 in Fig. 1, and by the employment of the screw 14, and vertical leg of the extension 11, the post is anchored to the base.

The recesses 4, which also may be termed cavities, are employed for the reception of the earth, which is tamped against the body portion 1, and when the cavities or recesses 4 are filled with the earth, below the level of the ground, the body portion 1, is secured from vertical movement and will be retained in such position until the earth has been removed from the recesses or cavities 4.

The combined reinforcing and coupling member, is not only employed for reinforcing the extension 7, but also for the upper part of the body portion 1, and this is obvious, by reference to the position, as shown of the combined reinforcing and coupling member, with respect to the extension 7 and body portion 1, as illustrated in Fig. 1.

When the screw 14 is mounted in securing position, the head 16, thereof, partly extends into the outer side of the extension 7.

The shank 10 of the combined reinforcing and coupling member, has its upper end positioned in close proximity to the top of the extension 7, whereby the screw or securing device 14, will be positioned in a like manner, so that the post 9 will be secured against the extension 7, in proximity to the top thereof, and as before stated, the screw 14, in connection with the vertical leg of the extension 11, will securely anchor the wooden fence post 9, to the base.

In the adaptation of a concrete base, in accordance with this invention, for use in connection with fence posts, it will be assumed that the base has been mounted in the ground, with the top 6 of the body portion 1, slightly raised above the ground level, or in alignment with the ground level. Now take any old wooden fence post that has had the butt end rotted off, bore a hole up in the said end, and set it upon the seat formed by the top 6 of the body portion 1, which is free of the extension 7, and position the fence post so that the opening in the bottom thereof, will have the upper end of the vertical leg of the extension 11 extend therewith. After the fence post has been mounted in the position as shown, the screw 14, is adjusted to engage the post, in a manner as

indicated at 15, in Fig. 1. By this arrangement, a firm and lasting post is set up. It is possible, to use any length of material in connection with the base, whether the material is short, and by providing for such employment, a great saving can be had in the building of fences; and as for a vineyard post, the base would be very valuable, as it could be set in the ground and a new post placed on as needed without molesting the vines. It is well known, that when tearing down old fences, that the posts are found rotted off at the ground, and that above the rotted end of the post, there remains about four or five feet of the best seasoned post that one could obtain, but that, such length cannot be used, owing to the fact that they are too short, but by utilizing a concrete base, in a manner as set forth, the said short length of seasoned posts can be readily secured in position and employed for use in connection with the setting up of fences.

Although the preferred embodiment of the invention is as described and illustrated, yet it is to be understood that changes in the details of construction can be had, which will fall within the light of the invention as claimed.

What I claim is:—

1. A base for fence posts comprising a body portion formed throughout of concrete and having an integral concrete vertically disposed extension projecting from one side of the top thereof, a metallic combined reinforcing and coupling member embedded in said extension and body portion and further having one terminal projecting through and extending a substantial distance above the other side of the top of the body portion and providing securing means for engaging in the bottom of a post seated on the top of the body portion, and means extending through said member and through said extension and engaging in the post for securing it against the extension.

100

105

2. A base for fence posts comprising a body portion formed throughout of concrete and having an integral concrete vertically disposed extension projecting from one side of the top thereof, a metallic combined reinforcing and coupling member embedded in said extension and body portion and further having one terminal projecting through and extending a substantial distance above the other side of the top of the body portion and providing securing means for engaging in the bottom of a post seated on the top of the body portion, and means extending through said member and through said extension and engaging in the post for securing it against the extension, said member having its other end provided with an eye and through which extends said means.

115

120

125

3. A base for fence posts comprising a

130

- body portion formed throughout of concrete and having an integral concrete vertically disposed extension projecting from one side of the top thereof, a metallic combined 5 reinforcing and coupling member embedded in said extension and body portion and further having one terminal projecting through and extending a substantial distance above the other side of the top of the 10 body portion and providing securing means for engaging in the bottom of a post seated on the top of the body portion, and means extending through said member and through said extension and engaging in the 15 post for securing it against the extension, said member having its other end provided with an eye and through which extends said means, said eye and said means positioned in proximity to the top of said extension.
- 20 4. A concrete base for fence posts comprising a body portion having its top provided with a vertical extension, a combined reinforcing and coupling member embedded in the extension and body portion and further projecting through the top of said body portion to provide a fence post securing means, and a fence post securing element extending transversely of and projecting from the inner side of said extension.
- 25 5. A concrete base for fence posts comprising a body portion having its top provided with a vertical extension, a combined reinforcing and coupling member embedded in the extension and body portion and further projecting through the top of said body portion to provide a fence post securing means, and a fence post securing element extending transversely of and projecting from the inner side of said extension.
- 30 6. A concrete base for fence posts comprising a body portion having its top provided with a vertical extension, a combined reinforcing and coupling member embedded in the extension and body portion and further projecting through the top of said body portion to provide a fence post securing means, and a fence post securing element extending transversely of and projecting from the inner side of said extension.
- 35 7. A base for fence posts comprising a body portion provided at its top with an extension and a fence post supporting seat, said seat arranged at one side of the base of said extension, said body portion and extension formed of concrete, a combined hook-shaped metallic reinforcing and coupling member embedded in and extended lengthwise of said extension and having its hook portion embedded in and projecting from the upper part of the body portion, that part of said member projecting from the top of said body portion extending a substantial distance above said seat and spaced from said base of the extension and engagable in the bottom of the fence post supported on the seat, and a hold fast device 70 extending through and projecting from the inner side of said extension and engageable in the side of the fence post.
- 40 8. A base for fence posts comprising a body portion provided at its top with an extension and a fence post supporting seat, said seat arranged at one side of the base of said extension, said body portion and extension formed of concrete, a combined hook-shaped metallic reinforcing and coupling member embedded in and extending lengthwise of said extension and having its hook portion embedded in and projecting from the upper part of the body portion, that part of said member projecting from the top of said body portion extending a substantial distance above said seat and spaced from said base of the extension and engageable in the bottom of the fence post supported on the seat, and a hold fast device 75 extending through and projecting from the inner side of said extension and engageable in the side of the fence post, said device extending through the upper terminal of said member and positioned in proximity 80 to the top of said extension.
- 45 9. In testimony whereof, I affix my signature hereto.

FRANK HOBART.
